TELEPHONE SYSTEM

Alexander Brune Preuss, Berlin-Charlottenburg, Germany, assignor to Siemens & Halske Aktiengesellschaft, Siemensstadt near Berlin, Germany

Application October 7, 1931, Serial No. 567,481, and in Germany October 10, 1930

11 Claims. (Cl. 179—18.)

In order not to increase the number of selecting stages to be used for a connection in telephone systems with a plurality of exchanges above the number of stages necessitated by the 5 number of connecting lines and also in order to avoid differently placed subscribers' numbers as well as to facilitate the setting up of connections by keeping the number of stations associated with the connecting line numbers as low 10 as possible, it has been suggested to seize a plurality of lines outgoing in various directions or to let the calling station simultaneously set a plurality of switches in various exchanges. These arrangements which are of special advantage 15 for certain circuits are in other cases encumbered by disadvantages which cannot be discounted either in technical or economical regards.

In order to avoid a simultaneous seizure of 20 lines extending in different traffic directions it has been suggested to arrange—by the arrangement of a special impulse sender at the subscriber's station—that the seizure of a connecting route outgoing in a certain traffic direction is 25 initiated in dependence upon the impulse series, which arrangement necessitates complications at the impulse sender associated with the subscriber's station.

The object of the invention is to bring about 30 an arrangement by means of which, as far as possible, all disadvantages accompanying known arrangements as well as an increase of selecting stages above the number necessitated by the number of subscribers' stations have been eliminated in a simple manner. The quantity of 35 special auxiliary devices necessary to satisfy all technical and operative demands are further brought to a minimum. The invention solves the problem by arranging that a numerical impulse receiver over which connections of certain 40 traffic directions are set up is set by means of a switch over which connections of other traffic direction extend.

Embodiments of the invention are shown in 45 the drawings to which embodiments the invention, however, is not limited. Fig. 1 is a trunking diagram showing the general layout of a telephone system embodying the invention; Fig. 2 is a circuit diagram showing more in detail the 50 essential features of Fig. 1; while Fig. 3 is a circuit diagram showing a modification of the system shown in Fig. 2.

Referring now to Fig. 1, T_n represents a subscriber's station which has access to a group selector IGW over the preselector IVW. At the

first number impulse which is sent out for the setting of the group selector IGW an impulse for the switch MW which seizes a free group selector IGWb associated with another exchange is effected over the line ar . If the connection is to be set up internally, for example to the subscriber T_{n1} , the group selector IGW is set to a free line within the level 1, 5, 6, 0. The second group selector IIGWa is seized whereupon the connection is extended over the final selector LW 65 to the subscriber T_{n1} .

If a subscriber associated with another exchange, for example the subscriber T_{n2} , is to be called, the group selector IGW is set to one of the levels 2, 3, 4, 7, 8 or 9. When the group selector IGW is raised to these levels it sends out impulses for the setting of the group selector IGWb with the result that the succeeding impulse series sent out by the subscriber reaches 70 the group selector IIGW.

It should be noted that in the case of internal connections the switch MW is released at the hunting of the group selector IGW for a free line in the levels 1, 5, 6, 0.

In conjunction with Fig. 2 the setting up of a 80 connection will be described in which case it should be noted that the switch wiper dk of the group selector IGW together with the associated contact bank shown in Fig. 2 only refers to the shown embodiment to the extent of taking over 85 the functions of the contacts multiply connected to earth in the contact banks of the switch wiper bgw in which case the line $L1$ can be omitted. The operation of the switch wiper dk will be described in detail in a suitable paragraph. 90

When the subscriber at a subscriber's station T_n lifts his receiver, the preselector IVW is set to a free line, for example, the lines $La1$, $Lb1$, $Lc1$, in any known manner. Relays A and B are energized whereupon the following test circuit 95 is set up over line $Lc1$: earth, winding II of relays B and A, off-normal contact $14k$ of the group selector IGW, contacts $13v$, $1b$, wiper cwv of the preselector IVW, not shown switching devices in line Lc . By the energization of relay B the contact $1b$ is thrown over whereby the seizing relay C is energized. This relay actuates its contacts $5c$, $6c$, $7c$, $8c$, and $19c$. By the energization of relay A contacts $2a$, $3a$, and $4a$ are thrown over. By the throwing over of contact $2a$, a test relay P of the group selector IGW is earthed over contact $6c$, and by the throwing over of contacts $3a$ and $4a$ the following circuit is established: earth, contacts $20p$, $15k$, winding III 100 of relay V, contacts $4a$, $7c$, $3a$, rotary off-normal 105 selector IGW, contacts $13v$, $1b$, wiper cwv of the preselector IVW, not shown switching devices in line Lc . By the energization of relay B the contact $1b$ is thrown over whereby the seizing relay C is energized. This relay actuates its contacts $5c$, $6c$, $7c$, $8c$, and $19c$. By the energization of relay A contacts $2a$, $3a$, and $4a$ are thrown over. By the throwing over of contact $2a$, a test relay P of the group selector IGW is earthed over contact $6c$, and by the throwing over of contacts $3a$ and $4a$ the following circuit is established: earth, contacts $20p$, $15k$, winding III 110 of relay V, contacts $4a$, $7c$, $3a$, rotary off-normal selector IGW, contacts $13v$, $1b$, wiper cwv of the preselector IVW, not shown switching devices in line Lc .

- contact 16w, vertical magnet H, battery, earth. Relay V only is energized in this circuit. This relay actuates its contacts 9v, 10v, 11v, and 12v and 13v. By the throwing over of contact 13v 5 the following circuit for the exchange signal is set up: earth, winding I of the exchange signal repeater AZ, condenser K, contacts 13v, 14k, winding II of relays A and B, earth. Contact 9v has been opened, but this causes no special 10 switching operation. Contact 11v was also opened in order to disconnect the rotary magnet D while the impulse series was transmitted to the vertical magnet H. Contact 12v has been closed but this has not produced any switching operation. 15 When the subscriber has received the exchange signal he can commence dialling. As soon as the line loop is broken relay A will be deenergized. Relay B, however, being constructed as a slow-acting relay remains energized during the impulse series. At the first release of relay A contacts 2a—4a are restored to their normal positions. By the throwing over of contact 2a no 20 switching operation is performed as contact 22p has not yet been actuated and the contact 9v 25 is already opened. By restoring contact 4a to normal the following circuit is set up: earth, contacts 4a, 7c, winding II of relay V, contact 17d of the rotary magnet D, rotary off-normal contact 16w, vertical magnet H, battery, earth. 30 The vertical magnet lifts the switch wipers agw, bgw, cgw, and dgw one step so that they are placed just in front of the first level. The off-normal contacts 14k and 15k are thrown over. By the throwing over of contact 14k the circuit over 35 which the exchange signal was induced is opened. By the throwing over of contact 15k the following circuit for the starting relay R of the switch MW is closed: earth, battery, contact 19c, winding of relay R, contact 15k, contact 20p, earth. 40 Relay R is energized and actuates its contacts 24r and 25r whereupon the switch MW is caused to hunt for a free line.
- If after the first impulse relay A has been re-energized the contacts 2a—4a are again actuated. 45 By the throwing over to contact 4a the circuit for the vertical magnet H is opened whereby this is de-energized. Relay V does not release during the opening period of contact 4a and during the individual impulses sent out by the subscriber 50 as its winding I is short-circuited. This relay, therefore, operates as a slow-acting relay during the impulse series. The impulse arriving after the first impulse again actuates the vertical magnet H whereby the switch wipers are raised a further step. This interaction between relay A and the vertical magnet H is continued until the subscriber has finished sending out impulses. 55 Assuming that the subscriber has sent out ten impulses, the switch wipers agw, bgw, cgw and dgw 60 of the group selector will be located in front of the contact bank 0. If after the transmission of the first impulse series, relay A is maintained energized for an extended period before the subscriber again operates his dial, the relay V, operating as a slow-acting relay, releases, as it is disconnected from earth over contact 4a. On the release of relay V the following circuit for the rotary magnet D of the group selector is set up: earth, contact 20p, off-normal contact 15k, contact 11v, rotary magnet D, battery, earth. The rotary magnet D is energized with the result that the switch wipers agw, bgw, cgw, and dgw 70 located in front of the level 0 are operated. The rotary magnet D when energized closed contact 17d. The rotary off-normal contact 16w also

was opened at the first rotary movement. The following circuit is set up over contact 17d: earth, contact 17d, winding I of relay V, vertical magnet H, battery, earth. Only relay V is energized in this circuit, the vertical magnet H does not receive sufficient current. By the energization of relay V its contacts are actuated so that also contact 11v is thrown over which results in the circuit for the rotary magnet D being broken. The rotary magnet is deenergized and, under the assumption that the line outgoing from the first set of contacts of the contact bank 0 of the group selector IIGW is busy, will be re-energized as soon as relay V releases by the opening of contact 17d. The switch wipers are advanced one step whereupon relay V is again energized. This interaction continues until the switch wiper cgw encounters a free line, for example line La2, Lb2, Lc2. When this occurs the following circuit is set up: earth, battery, not shown switching devices at 80 the group selector IIGWa, relay C1, line Lc2, switch wipers cgw of the group selector IIGW, windings I and II of the test relay P, contacts 2a, 6c, earth. Relays P and C1 are energized. Relay P actuates its contacts 18p, 20p, 21p, 22p, and 23p. The winding II of relay P is short-circuited by the operation of contact 18p with the consequence that the found line will be guarded. Contact 20p breaks the circuit for the rotary magnet D and at the same time the circuit for 85 relay R. This relay releases and causes the release of the switch MW. Contact 21p is thrown over, which, however, does not cause any switching operation to take place. Contacts 22p and 23p now switch through the connection. The 90 impulsive receiving relay of the group selector IIGWa will now be brought under the influence of the calling subscriber. The impulses sent out by him are transmitted to the group selector IIGWa over the contact 2a in known manner. 95 Relay V is maintained energized during this impulse series so that the impulses sent out over contact 2a cannot influence the condenser K1 by the opening of contact 9v. When the first impulse arrives to the group selector IIGWa, relay 100 V is energized over earth, contact 4a, contact 7c, windings II and I of relay V, winding of vertical magnet H, battery, earth. The vertical magnet H is not energized. Relay V actuates its contacts and by the closing of contact 12v causes 105 a short-circuit of winding II of relay V with the result that this does not release on the transmission of impulses and also due to the operation of contact 4a intimately connected with the impulse series due to the short-circuit of winding 110 II, the relay being influenced in such a manner that it operates as a slow-acting relay, that is to say, it remains energized during the transmission of impulses. 115 If the connection is released by the subscriber 115 at the subscriber's station Tn replacing his receiver the relays A and B release. Relay B closes contact 1b, whereby relay C will be short-circuited. The contacts of relay C are restored to normal. By the short circuit of winding I of 120 relay P this relay is caused to release. Relay P opens its contacts and by the throwing over of contact 18p, breaks the test circuit. Relay C1 accordingly releases whereby the release of the succeeding switch IIGWa can be initiated. 125 By the throwing over of the contact associated with relays C and P the following circuit for the rotary magnet D is set up: earth, contact 20p, off-normal contact 15k, contact 11v, rotary magnet D, battery, earth. The rotary magnet is 130

energized in this circuit. The opening of contact 19c prevents the starting relay R from re-energizing when contact 20p is closed. The rotary magnet D, when energized, actuated contact 17d whereby relay V is energized over its winding I. Relay V breaks the circuit for the rotary magnet at contact 11v whereupon contact 17d returns to normal. The alternating interaction between winding I of relay V and the rotary magnet D continues until the switch wipers agw, bgw, cgw, and dgw have left the contact bank of the switch whereupon these drop down due to their own weight and take up their normal position. The off-normal contacts are thrown over due to this movement and the rotary off-normal contacts, for example 16w, are re-closed. After the opening of the off-normal contacts the group selector is restored to its normal position and thereby set in preparation for the setting up of a fresh connection.

It will now be assumed that the subscriber at a subscriber's station T_n has not selected any of the digits 1, 5, 6 or 9 in the first impulse series by which he can obtain a connection within the exchange $VSt1$, but as the first impulse series selected the digit 4 whereby he reaches the exchange $VSt2$ over the switch MW and the junction line La4, Lb4, Lc4.

When the group selector is seized relays C, A, B, and V are energized in the manner already described. At the transmission of the first impulse relay R is energized due to the operation of the off-normal contacts over the following circuit: earth, contact 20p, off-normal contact 15k, relay R, contact 19c, battery, earth.

By the energization of relay R contacts 24r and 25r are thrown over. By the throwing over of contact 25r the interrupter U will be connected to the rotary magnet D_{mw} of the switch MW. The wipers of the switch MW are advanced step-by-step. When the switch wiper cmw encounters a free line, for example the line Lc4, the following circuit is established: earth, battery, not shown switching devices, relay C2, line Lc4, relay X, switch wiper cmw , windings II and I of relay T, contact 24r, earth, in which circuit relays T, X and C2 are energized. By the energization of relay T contacts 26t, 27t, 28t, and 29t are actuated. By the opening of contact 29t the circuit for rotary magnet D is broken. By contacts 27t and 28t the line La3, Lb3 is switched through. Contact 26t short-circuits winding I of relay T with the consequence that the seized line will be guarded in known manner. Relay X opens contact 30x. Assuming that the lines reached by the switch MW are free, the x-contacts of the other relay X, located in the lines associated with the switch MW, are closed which prevents relay G from releasing. Relay G maintains its contact 31g closed. The normal position of this contact is indicated by dotted lines. It will thus be seen that as long as free lines can be reached by the switch MW the relay G is maintained energized. Only when a busy signal from all the outgoing lines is received relay G releases whereupon contact 31g takes up the normal position indicated by dotted lines, a switching operation, the purpose of which will be explained later. On the energization of relay C2 the contact 32c2 among others will be actuated whereby the group selector $IGWb$ is ready to hunt.

As it was assumed that a subscriber would send out four impulses the switch wipers agw—dgw of the group selector IGW are raised four steps.

At the end of this impulse series during which the relay A has been maintained energized an extended period the relay V, operating as a slow-acting relay, releases as already described. Contact 11v is closed by this operation and the following circuit for the rotary magnet D is set up: earth, contact 20p, off-normal contact 15k, contact 11v, rotary magnet D, battery, earth. Contact 16w is opened and contact 17d is closed. Relay V is hereby re-energized over its winding I which causes contact 11v to be re-opened. The rotary magnet releases and this interaction continues until the switch wiper cgw settles upon the fifth contact in the fourth level to which battery is supplied over contact 31g.

Upon the first rotary step made by the switch the following circuit is established: earth, junction line of the multiply connected contacts in the levels 2, 3, 4, 7, 8, and 9 of the switch wiper bgw associated with the group selector IGW , switch wiper bgw, contact 10v of the energized relay V (closed on the energization of the rotary magnet D) contact 22p, switch wiper agw of the group selector, first contact in the contact bank 4 of the switch wiper agw, line La3, contact 27t, switch wiper amw of the switch MW, line La4, relay A1, battery, earth. Relay A1 will be energized by this impulse and is utilized for the setting of the first group selector $IGWb$ in any known manner. Upon the energization of relay V at the first rotary step of the group selector IGW the circuit for the rotary magnet D is broken by contact 11v. Rotary magnet D releases whereupon contact 17d is restored to normal. Relay V is short-circuited over its winding I and thereby releases. At this release contact 10v is opened and contact 11v closed. This ends the first impulse sent out over the line La3. When the switch wipers agw—dgw are set to the second contact in the level 4 at the succeeding energization of the rotary magnet D, relay V also is caused to be re-energized over contact 17d. Contact 10v is closed whereby a second impulse reaches relay A1 over the line La3, La4. When the switch wipers of the group selector reach the fifth contact of level 4 a test circuit is established which brings the switch to rest as already described in a previous paragraph. This test circuit extends over: earth, battery, contact 31g, fifth contact in level 4 of the contact bank of the switch wiper cgw, switch wiper cgw, windings I and II of relay P, contacts 2a, 6c, earth. Relay P is energized and brings the group selector to rest in the manner already described. By the opening of contact 20p the circuit for relay R will be broken over the switch wiper dgw (which can be constructed as a multiple contact) if a locking circuit for relay R has not been set up. This extends over: earth, switch wiper dgw, segment 4 in the level 4 of the switch wiper dgw, resistance W_{13} , winding of relay R, contact 19c, battery, earth. The resistance W_{13} is so calculated that relay R is maintained energized whereas the rotary magnet D receives insufficient current over contact 11v and resistance W_{13} to be energized. As contact 10v was closed at each rotary step of the switch an impulse is sent out at each closing of contact 10v which reaches relay A1 of the group selector $IGWb$ over the multiply-connected earth at the contacts in the contact banks of the switch wiper bgw over contact 10v, etc.

It is not absolutely necessary to have the contact banks of the group selector connected up in the manner shown in Fig. 2. Instead of the con-

acts brushed by the switch wiper *bgw* to which earth is connected, a multiple contact *dk* can be provided the contact bank of which is diagrammatically shown in level 3. In such a case the line *Li* can be omitted. Impulses can be generated by the opening and closing of contact *10v* in the manner already described and shown. In such a case the segment swept by the switch wiper *dk* can be made of a continuous metal strip not split up into individual contacts. The transmission of impulses will be limited by the energization of relay *P*, contact *22p* among others being thrown over.

If the impulses are to be generated by the auxiliary contact bank brushed by the switch wiper *dk*, contact *10v* can be dispensed with. In such a case the switch wiper *dk* and the contacts brushed by this wiper are so designed that the switch wiper *dk* when sweeping over the individual earthed contacts of the contact bank produces sufficiently long make and break intervals.

A further method of generating impulses can be effected by the segment, brushed by the switch wiper *dk*, being undivided in which case contact *10v* can be dispensed with, the switch wiper *agw* and the contacts swept by this wiper being so constructed that when the switch wiper *agw* sweeps the contact banks make and break intervals suitable to make up the impulse series can be obtained.

It should be noted that in such cases in which the switch wiper *bgw* is not necessary to the impulse series the contact banks brushed by this wiper need not be connected in the manner shown in the drawings. In such a case the contacts over which connections must extend to the switch *MW* can, moreover, be combined in any known manner.

It is also not necessary to restrict the impulse series by the energization of the test relay. The impulse series, for example, could be ended by utilizing the level contact *dk* as an impulse generator, as the lever contact *dk* possesses earthed contacts only in the first positions whereas the last positions are designed as a one-piece segment. The impulse series is then restricted in the moment the level contact *dk* reaches this one-piece segment. The switch can be brought to rest in any desired position in which the level contact *dk* brushes the one-piece segment. The contact *22p* must then be designed as a light contact.

When the impulse series generated by the group selector *IGW* is ended the switch *IGWb* will also be set.

The succeeding impulse series sent out by the subscriber extends over the group selector *IGWb* to any of the devices known per se.

When the connection is released by, for example, the subscriber at station *Tn* replacing his receiver a circuit for the rotary magnet is again set up over the releasing contact *20p* as already described and the switch wipers of the group selector are restored to normal. On the release of relay *C* contact *19c* is opened. Relay *R* releases and opens contacts *24r* and *25r* whereby also the connection set up over the switch *MW* is released.

When a busy signal is obtained from all the lines outgoing from the switch *MW* all the *X* relays are energized as already mentioned. Relay *G* releases at the same time opening contact *31g*. The group selector *IGW* then cannot test to the 5th contact in level 4 as described, but reaches position 11 in which the rotary off-normal

contact *w11* is closed. Relay *P* is energized over battery, resistance *W12*, rotary off-normal contact *w11*, windings I and II of relay *P*, contacts *2a* and *6c*, earth. Contact *20p* is opened whereby relay *R*, which was maintained energized over the off-normal contact *15k* and contact *20p*, releases. The locking circuit for relay *R*, which extends over the segment 4 when the switch wipers *agw*—*dgw* are located in the positions 1—10, is also opened as the switch wiper *dgw* in position 11 has left the segment. The started switch *MW* is brought to rest by the release of relay *R*. The subscriber at station *Tn* receives the busy signal which is transmitted over earth, winding I of the busy signal repeater, rotary off-normal contact *1w11*, windings II of relays *A* and *B*, earth. When the subscriber replaces his receiver the relays *C*, *A*, *B*, and *P* release as already described. Relay *P* among others closes contact *20p* whereby the rotary magnet *D* receives an impulse and restores the switch to normal.

It should be noted, further, that a circuit arrangement obviously can be provided which brings the switch *MW* to rest on the eleventh step when a busy signal is received from all the lines which can be reached by this switch. It should also be mentioned that the impulses sent out during the free hunting of the group selector *IGW* when a busy signal is received from all the lines outgoing from the switch *MW* are ineffective as the switch *MW* has not hunted and the contact *27t* has not yet been closed.

An embodiment is shown in Fig. 3 which indicates that already at the vertical movement of the group selector impulses are generated for the setting of another group selector. Apart from this the arrangement corresponds to the arrangement according to Figs. 1 and 2. The group selector *IGW* is to have access to the internal group selectors, for example, group selector *IGWa* over its levels 1, 2, and 3, while it generates impulses for the setting of other group selectors, for example, *IGWb* when set to the levels 4—0. The switch *MW* in this embodiment is now located in the front of the first group selector *IGW* instead of behind same.

It is now obvious that a further distribution of the contact banks can be effected, for example, the levels 1, 2, and 3 being provided for internal connections whereas the levels 4, 5, 6, 7, 8, 9, and 0 can be used for the setting up of connections over group selectors, for example, a group selector *IGWb* in another exchange. If a subscriber requires a connection with a free line in the levels 1, 2, and 3 the same switching operations are initiated as were already described in conjunction with Fig. 2. When the subscriber sends out the first impulse a circuit for relay *R* is set up over off-normal contact *15k* extending as follows: earth, off-normal contact *15k*, contact *21p*, relay *R*, contact *19c* (closed on the seizure of the group selector) battery, earth. Contacts *24r* and *25r* are actuated when relay *R* is energized, this causing the switch wiper *cmw* of the switch *MW* to be earthed and the circuit for the rotary magnet *Dmw* to be set up. The switch *MW* hunts for a free outgoing line in the manner already described in conjunction with Fig. 2. If the connection extends internally the contact *21p* is opened at the energization of the test relay *P*, this causing relay *R* to release. Relay *R* effects the release of the switch *MW* with the result that the line seized by this switch is released.

If the subscriber requires a connection which

effects another exchange over the switch MW he dials one of the digits 4—0 according to the desired direction. Assuming that the subscriber has dialled 5 after having lifted the receiver 5 and after energization of relays C, A, B, and V take place in the manner already described in conjunction with Fig. 2 the following switching operations will be effected at the first release of relay A: The contacts 2a, 3a, 4a, and 5a take 10 up the positions shown in the drawings. When this occurs the following circuit for the vertical magnet H is set up accordingly: earth, contact 5a, contact 9c, winding II of relay V, contact 17d, lower contact at the rotary off-normal contact 16w, winding of vertical magnet H, battery, earth. The vertical magnet H is energized and lifts the switch wipers agw, bgw, cgw, and Dk one step. The off-normal contacts 13k, 14k, and 15k are thrown over. By the closing of contact 15k, the switch MW starts as already described 20 to hunt for a free line, for example, the line La4, Lb4. The contact 14k prepares the circuit for the rotary magnet. The contact 13k disconnects the exchange signal AZ from the subscriber's line. If relay A is re-energized after the first 25 impulse the contacts 2a—5a are thrown over. Contact 4a causes a short circuit of windings II and I of relay V whereby this does not release during the impulse series due to its retardation. When relay A releases at the second impulse the 30 contacts associated with this relay take up the positions shown in the drawings. The throwing over of contact 2a causes no interruption in the operations as contact 22p has not yet been actuated but contact 19v has been maintained open during the impulse series. If the vertical magnet H is energized at the second impulse the switch wipers of the group selector IGW are connected 35 up in front of the second contact bank. These switching operations are repeated until the group selector arrives in front of the contact bank 4. When this occurs the earthed contact Dk is connected to the level contact 4 whereby a circuit to the connected group selector IGWb 40 is set up as follows: earth, level contact Dk, contact segment 4, line si, contacts 3a, 22p, line La3, contact 27t, wiper amw of the switch MW, line La4, relay A1 at the group selector IGWb, battery, earth. Relay A1 is energized and effects 45 the setting of the group selector IGWb on to the first level. When the fourth impulse has arrived the contacts 2a—5a are thrown over whereby also the impulse arriving to relay A1 is ended by opening contact 3a.

50 It will be mentioned in this connection that contact 3a is not absolutely necessary. The impulse series could, for example, be transmitted over the level contact dk if this contact or the contacts swept by the same are so designed that sufficiently long make and break intervals are obtained during the brushing of the level contacts 1—0.

55 When the group selector IGW is raised a further step by the succeeding impulse the contact Dk will be found on the level contact 5. In such a case a further impulse will be transmitted to a relay A1 which will be cut off as soon as relay A is caused to be energized. When the impulse series is ended, that is to say, when relay A has been maintained an extended period, relay V 60 will also release. As a result a circuit for the rotary magnet D will be set up over the contact 11v. The rotary magnet D causes the rotation of the switch wipers agw—Dk of the group selector in the fifth contact bank. Contact 16w

is opened and contact 17d closed whereby relay B is energized. Relay V among others opens contact 11v causing the rotary magnet D to be disconnected from battery. The switch wipers of the group selector are advanced by the interaction between relay V and the rotary magnet D until relay V is energized. This will occur as soon as the switch wiper cgw has reached the tenth contact in level 5 when the following test circuit is set up: earth, battery, contact 31g, tenth 80 contact in the contact bank 5, switch wiper cgw, windings II and I of relay P, contact 2a, contact 7c, earth. Relay P is energized and actuates its contacts. By means of contact 18p it prepares a locking circuit for itself. Contact 20p opens 85 the energizing circuit for the rotary magnet D. Contact 19p prepares a circuit for the short-circuit of winding II of relay V. By the opening of contact 21p the energizing circuit for relay R will be opened. This relay, however, does not release as the level contact Dk connects earth to relay R over the resistance W1. Contacts 22p and 23p have now switched through their connection.

The subscriber is now in a position to set the 100 switching devices located behind the group selector IGWb by the sending out of further impulse series. These impulses do not influence the magnets D and H. Relay V is energized at the first impulse by the throwing over of contact 5a to normal over earth, contact 5a, contact 9c, windings II and I of relay V, rotary magnet H, battery, earth. The vertical magnet H is not energized in this circuit due to the special resistances connected with relay V. Relay V actuates 105 its contacts and opens contact 19v in order to prevent the impulses sent out over contact 2a from charging the condenser Ko1. The winding II of relay V is short-circuited by contact 12v with the result that this relay does not release 110 during the impulse transmission as the short-circuiting of winding II of relay V causes this relay to function as a slow-acting relay.

It should also be noted that by applying 120 battery to the tenth contact of the contact bank 4—0 of the switch wiper cgw over contact 31g it will be achieved that the group selector is brought to rest on the tenth stop. This precaution has been taken in order to restore the switch to normal with as few steps as possible when releasing. The switch could obviously be brought to rest on any other contact in the corresponding contact bank.

When the connection is to be released the subscriber Tn1 replaces his receiver whereupon the 130 relays A, B, and C release. Relay C closes contact 8c and causes the release of relay B by short-circuiting the winding II of this relay. Relay R is disconnected from battery by means of contact 19c and releases, thereby releasing the 135 switch MW. The switches located behind the group selector IGWb are also released by the opening of the circuit for the windings of relays T, X, and C2 when these relays released. On the closing of contact 20p a circuit for the rotary 140 magnet D is set up which extends over earth, contacts 20p, 14k, and 11v. The rotary magnet sets the switch wipers of the first group selector IGW into position 11. At the same time it causes contact 17d to be closed. Relay V is energized over its winding I and opens contact 145 11v. This contact causes the de-energization of the rotary magnet which in turn causes relay V to release by the opening of contact 17d. The rotary magnet D then receives an impulse where- 150

upon the switch wipers of the group selector leave the contact banks and drop into their normal position by their own weight. The off-normal contacts 13k, 14k, and 15k are opened whereby the original position of the system is again restored.

Should all the lines outgoing from the switch MW be busy at the initiation of a connection over this switch relay G also will have released.

10 This relay opens contact 31g. This causes the group selector IGW to hunt freely until it reaches position 11. In this position the test relay P will be energized over the resistance Wi and contact w11. The test relay P opens the circuit for relay R by means of contact 21p. Relay R releases as also the level contact Dk is set in position 11, that is to say has left the associated segment with the result that the earth applied to the level contact cannot maintain relay R energized. The switch MW is released and the subscriber received the busy signal over contact 1w11. When he replaces his receiver relays A, B, and C are released. Relay C causes relay P to be short-circuited by means of contact 8c. Relay P also releases and causes the setting of the switch IGW to normal in the already described manner.

If, at the setting up of internal connections all lines outgoing from the first group selector 30 in the corresponding level are busy relay P will only be energized when the switch has reached the position 11. In such a case the switch MW which has been set at the first number impulse will be released by the opening of contact 21p. 35 The subscriber then receives a busy signal whereupon he can release the initiated connection by replacing his receiver.

What is claimed is:

1. In a telephone system, a first exchange, a second exchange, a trunk line extending from said first exchange to said second exchange, a switch at said first exchange for setting up local connections, and means controlled by the setting of the switch at said first exchange for setting the switch at said second exchange over said trunk line, said means including contact groups in the switch at said first exchange, multiple contacts in said contact groups the number of which corresponds to the groups of connected lines in the switch at said second exchange, and means controlled by said multiplied contacts for generating impulses for setting the switch in said second exchange.

2. A system as set forth in claim 1, in which the impulses are generated by means of contacts in the contact bank of the switch in said first exchange which are brushed by the switch wiper.

3. A system as set forth in claim 1, in which means are provided for transmitting impulses over the wipers of the switch at said first exchange located in the speaking leads.

4. A system as set forth in claim 1, characterized by the provision of a locking device in said first exchange to prevent the switch in said first exchange, which is operated to set switches in said second exchange, from seizing a trunk to said second exchange when the trunks thereto are not available.

5. In a telephone system, a first exchange, a second exchange, a vertical and rotary switch in the first exchange, local trunk lines connected in one or more levels of said switch, means for

causing said switch to select any level and for automatically rotating the same over the selected level, trunks extending from said first exchange to said second exchange, means for selecting an idle one of said trunk lines, and means effective if said switch selects a non-local level for transmitting impulses over the selected trunk line during the rotation of said switch over the selected level.

6. In a telephone system, a switch having a primary movement and a secondary movement, a plurality of other switches, means responsive to the primary movement of said first switch for selecting one of said other switches, and means effective during the secondary movement of said first switch for transmitting impulses to the selected other switch.

7. A system as claimed in claim 6, in which the number of impulses transmitted is determined by the extent of the primary movement of said first switch.

8. In a telephone system, a switch having a primary movement and a secondary movement, a plurality of other switches, means responsive to the primary movement of said first switch for selecting one of said other switches, and means responsive to a continuation of said primary movement for transmitting impulses to the selected other switch.

9. A system as claimed in claim 8 in which the number of impulses transmitted to the selected other switch is governed by the extent of the primary movement of said first switch.

10. In an automatic telephone system, a first exchange, a calling subscriber's line appearing therein, a second exchange, trunk lines interconnecting the exchanges, a switch in the first exchange, a hunting switch individual thereto for selecting an idle one of said trunk lines, switches in the second exchange accessible over said trunk lines, means controlled over said subscriber's line for directly operating the switch in said first exchange a predetermined number of steps, means responsive to the directive operation of said switch for causing said hunting switch to select an idle switch in the second exchange over one of said trunk lines, means for automatically controlling the switch in the first exchange to take the same number of steps taken previously by the directive operation, and means for automatically controlling the switch in the second exchange, the automatic control of the switch in the second exchange being governed by the stepping action of the switch in the first exchange under its automatic control.

11. In a telephone system, a switch having a primary and a secondary movement, a plurality of other switches, means responsive to the primary movement of said first switch for selecting one of said other switches, means depending upon the extent of the primary movement of said first switch for determining the extent of the secondary movement of the switch, means controlled by the secondary movement of said first switch for transmitting impulses to the selected other switch to operate the same in a primary movement, the extent of the primary movement of said second switch being governed by the extent of the secondary movement of said first switch, and means for automatically controlling said second switch in its secondary movement.

ALEXANDER BRUNO PREUSS.
